UNITED STATES PATENT OFFICE.

FRANZ PALLENCBERG, OF DORTMUND, GERMANY.

FUEL-FEEDING DEVICE FOR FURNACES.

No. 865,723.

Specification of Letters Patent.

Patented Sept. 10, 1907.

Application filed June 22, 1906. Serial No. 322,932.

To all whom it may concern:

Be it known that I, FRANZ PALLENCBERG, a citizen of the German Empire, and a resident of Dortmund, Germany, have invented a new and useful Improved 5 Fuel-Feeding Device for Furnaces, of which the following is a full, clear, and exact description

The present invention relates to that class of fuel feeding devices for furnaces, in which the hopper is provided with a fuel breaking mechanism and a distributing ring having inclined distributing surfaces is mounted to rotate below the hopper. Some of these rings are provided with distributing surfaces having various angles, *i. e.* the angle of inclination differs at different points of the ring, and in this connection 10 the fuel is very liable to take the shortest way over the distributing surface and consequently uneven distribution ensues.

The object of the present invention is to provide means for guiding the fuel properly over the said distributing surfaces, so that they shall properly fulfil the purpose for which they were intended.

In order to render the present specification easily intelligible reference is had to the accompanying drawing in which similar letters of reference denote similar 20 parts throughout the several views.

Figure 1 is a vertical central section through the whole fuel feed device, Fig. 2 is a plan view of the distributing ring, Fig. 3 is a cross section through the ring on line C—D of Fig. 2, Fig. 4 is a cross section through 30 the ring on line E—F of Fig. 2, Fig. 5 is a vertical central section of a modified form of the apparatus, Fig. 6 is a part plan of the same and Fig. 7 is a plan view of the modified form of distributing ring.

Referring first to Figs. 1 to 4:—For the purposes of 35 the present specification the invention is described as in connection with an ordinary gas generator having a stack of fuel. To the top of the generator, the supporting plate *a* for the feed device is attached. This plate is provided with an outer upwardly extending 40 flange *a'* and an inner inclined annular flange *a''* which serve to form a water seal with the downwardly slanting flange *b'* of the carrier plate *b* for the feed hopper and distributing ring *c*. The latter is either attached to the plate *b* or made in one piece with the same. The 45 plate *b* has an upper horizontal flange provided with ratchet teeth *g* in which a pawl *h* engages, so that the said plate *b* and with it the distributing ring may be turned either by hand or by any suitable driving mechanism. The annular dip formed at the top of the 50 plate *b* by means of the inner vertical flange *o* forms the water seal for the downwardly extending flange *n* of the feed hopper *l*, which may also be supported on the plate *a* by means of suitable legs *l'*. The hopper *l* is closed in the known manner by means of the upper hopper *p* and the cover to the same.

The distributing ring *c* (Figs. 3 to 4) is in the form

of a hollow irregular truncated cone having an eccentric passage through the same having a vertical wall *c'* at one side of the same formed by the eccentricity of the upper surface or plane of the opening as in Fig. 3, 60 thus forming a passage through the ring having one vertical wall *c'* gradually merging into the opposite inclined wall *x*. The upper edge of the orifice may be oblong or circular as shown at Fig. 3. The ring is hollow and may be supplied with cooling water through the inlet *f* (Fig. 1). The plate *b* and the distributing ring *c* are provided with a suitable number of supporting rolls *d* adapted to run on a suitable angle iron or track *e*, supported on and bolted to the plate *a*, so that the whole may be easily turned without causing too 70 much friction.

The distributing ring *c* is mounted in the opening of the supporting plate *a*, so that its inclined side will lie a suitable distance from the inclined flange of the supporting plate to form a crescent shaped opening 75 around the said ring and between it and the supporting plate as indicated at *y*, while the vertical side or part of the said ring closes practically against the top of the inclined flange of plate *a* (Fig. 1). The orifice or through way through the distributing ring is partially 80 closed by a top wall *i*, which is so formed that it will leave a crescent shaped opening as at *z* at the upper surface of the ring, the lower surface of the orifice being circular as will be readily understood on reference to Figs. 1 and 3. Thus the fuel coming from the 85 hopper will be evenly distributed through two crescent shaped openings one *z* revolving with the ring and the other *y* being continually formed at successive points around the inclined flange of plate *a* and between it and the outer surface of ring *c*. Now in 90 order to prevent the fuel from taking the shortest cut over the distributing surfaces of the ring *c*, which is particularly liable with the longer, or less inclined surfaces, both the interior and exterior distributing surfaces of the said ring are provided with ribs *d'* extending radially down the same, which ribs effectively prevent the fuel from falling off the distributing surfaces, as it were.

The interior of the hopper is provided with a series of vertically disposed inwardly projecting teeth or 100 flanges *m*, while the ring *c* is provided with a top cover *j* in the form of a cone having spirally arranged ribs thereon as at *k*, which coöperate with the ribs or teeth *m* of the hopper *l* to reduce the pieces of fuel to an uniform size, before they pass through the two 105 crescent shaped openings of the distributing ring.

The operation of the device is such that when the distributing ring is turned by hand or by suitable mechanism, the fuel will first be reduced to the desired size and will then pass through the outer crescent shaped opening at *y* to the outer parts of the cross sectional area of the fuel bed and through the 110

opening z in the distributing ring c to the inner parts of the fuel bed area, so that the fuel will, by the rotation of the distributing ring, be evenly distributed over all the cross sectional area of the bed. The spiral 5 ribs k serve to feed the fuel to the annular space between the lower edge of the hopper l and the outer edge of the cover j , through which the fuel passes to the crescent shaped openings y and z . The cover j might of course be so arranged or mounted so as to 10 remain stationary and the hopper l turned in some suitable manner if desired.

In the modification shown in Figs. 5 to 7, the arrangement of most of the parts is substantially the same but the distributing ring is modified in form. 15 In this case the conical distributing ring c^2 is flattened as at r and provided at this point with an inwardly extending depression or recess s , flared at the bottom and having an incline corresponding approximately with that of the hopper l . Thus the fuel will 20 be directed through this depression or recess and by

the slanting wall of the hopper l , so that it will be evenly distributed over the central part of the bed, while it will pass over the exterior surface of the ring to the outer parts of the bed in a manner similar to that described with reference to Figs. 1 and 2. In 25 this case also the distributing surfaces are provided with the guide ribs d' for the purpose specified.

I claim as my invention:—

In a fuel feeding device of the class specified, comprising a hopper having fuel breaking mechanism therein, a rotary distributing ring mounted beneath said hopper, said ring having outwardly inclined distributing surfaces of varying inclination, the combination of ribs extending downwardly and spreading outwardly along said distributing surfaces.

30

In testimony whereof I affix my signature in the presence of two witnesses.

FRANZ PALLENCBERG.
